CLAIM

The ornamental design for a set of pallet legs, as shown and described.

DESCRIPTION

FIG. 1 is a perspective view of the set of pallet legs showing the environment of the design, a pallet, in phantom; FIG. 2 is a top plan view of the set of pallet legs with the outline of its environment in phantom;

FIG. 3 is a side elevational view of the set of pallet legs of the present invention as seen from orientation 3—3 of FIG. 1; and,

FIG. 4 is a side elevational view of the set of pallet legs of the present invention as seen from orientation 4—4 of FIG. 1.

The broken line showing is for illustrative purposes only and forms no part of the claimed design.
